UNITED STATES PATENT OFFICE.

SIDNEY GEORGE BROWN, OF LONDON, ENGLAND.

TELEPHONY.

1,061,813.

Specification of Letters Patent. Patented May 13, 1913.

Application filed February 4, 1910. Serial No. 542,023.

To all whom it may concern:

Be it known that I, SIDNEY GEORGE BROWN, a subject of the King of Great Britain, residing at 4 Great Winchester street, in the city and county of London, England, have invented certain new and useful Improvements in or Relating to Telephony, of which the following is a specification.

10 This invention relates to telephony and consists in certain improvements whereby telephonic systems are rendered more efficient than heretofore and the intensity of the received sounds is increased.

15 The improvements can be used in connection with a microphonic transmitter, or with a relay for the purpose of magnifying the electric or sound waves in the receiver.

Experiments have been conducted at 20 various times with a view to determining the best conducting material or metal to use for the variable resistance contact devices employed in telephonic apparatus; carbon, osmium, iridium and various oxidizable and 25 non-oxidizable metals or materials possessing conducting or other properties that would render them efficient as resistance varying devices have been experimented with, but these experiments and researches 30 have heretofore led to the conclusion that carbon, as a conducting material for the particular purpose referred to, (owing to its comparatively high resistance and the nature of the electric current ordinarily employed) was the only material capable of 35 yielding satisfactory results.

I have found by experiment that the efficiency of a telephonic system is greatly enhanced by using in the construction of the 40 contact device a grain or grains of osmium-iridium alloy; to obtain high efficiency the resistance of the circuit in which such a contact device is employed should bear the same relationship to the resistance of the metallic 45 contact device itself as the resistance of the telephonic circuits connected with ordinary carbon contact devices bear to the resistance of the latter. It is therefore proposed, according to the present invention, to substitute for the ordinary carbon contact devices 50 heretofore employed contact devices composed of grains or fragments of osmium-iridium alloy. Osmium-iridium alloy occurs in nature in the form of grains and I 55 employ it in its natural condition for the purpose of the present invention. The

physical properties of iridium render it capable of being formed into sheets owing to its comparative softness, and although for this reason it is not effective as a microphone 60 material it is especially useful for forming hard faces with which grains of the aforesaid other metals or the alloy make contact.

The contact device formed by the use of the aforesaid metal or alloy may be arranged 65 as a single contact or point, or, by the use of the metal in the granular form, as a multiple contact. In either case the voltage on the contacts should be low; for example in the single form of the contact, the voltage 70 may be of the value of say, one-half a volt, while in the multiple form of the contact the voltage may be of higher value—say one and one half to two volts, there being in the latter case many more points of contact over 75 which the current is distributed than in the former case. If the grains are employed in the form of a column it would be possible to use a still higher voltage. The grains may however be arranged in a number or series 80 of cells.

The lowness of the resistance of the contact device when of the granular form will depend upon the number of contact points provided by the grains and upon the initial 85 pressure to which the same are subjected. When the contact device is used in connection with a relay the sensitiveness thereof is regulated by the amount of grains employed. 90

A satisfactory construction of contact device consists of the natural grains of osmium-iridium alloy, arranged in a kind of cell formed between two hard faces which are adapted to act or press upon the hard grains, 95 the latter being retained in position by suitable means such as those now used in the carbon contact device of the ordinary telephone transmitter, or by an encircling band of india rubber or the like arranged so as to 100 inclose the space between the faces, and yet permit of the free vibration of either or both of them.

In order that the said invention may be clearly understood and readily carried into 105 effect, I will proceed to describe the same more fully with reference to the accompanying drawings in which I have represented several diagrammatic embodiments of the invention.

In the drawings:—Figure 1 indicates a 110 telephonic transmitter in which the contact

device is of the character hereinbefore described. Fig. 2 is a modified form of transmitter in which the vibratory diaphragm is attached to a pivoted member, which operates the movable contact piece pertaining to the contact device. Fig. 3 illustrates an arrangement whereby the contact device may be maintained cool by water circulation. Fig. 4 shows a telephonic relay in which the metal of the contact device is in the form of grains disposed in a suitable containing cell. Fig. 5 is a similar form of relay in which the initial resistance is adjusted electrically. Fig. 6 represents a relay in which the contact device comprises a single contact piece or point. Fig. 7 is another form of such a relay.

Referring to Fig. 1, a is the mouth-piece of the transmitter, and a' the diaphragm, which is set in vibration when the sound waves are directed through the mouthpiece so as to impinge on the said diaphragm. A contact piece a^2 is secured to the diaphragm in such a manner as to render it capable of participating in the movements of the diaphragm. This contact piece is arranged to act in conjunction with a fixed contact piece a^3 , which is mounted on a support a^4 from which it is insulated by any suitable means, such for instance as by a bushing of vulcanite or other insulating material.

If the member a^4 is made of insulating material the contact piece may be directly secured thereto. The contact pieces are faced with iridium and the space between these faces is converted into a cell a^5 by providing a covering a^6 of india rubber or other suitable flexible or yielding material which will be sensitive to the vibrations or movements of the movable contact piece a^2 resulting from the action of the sound waves on the diaphragm a' . Into the cell a^5 a few grains of osmium iridium alloy are placed, the said grains being about one-third or one-fourth the size of the carbon granules employed in an ordinary carbon transmitter. The aforesaid cell may be approximately similar to the present carbon cell but of much smaller dimensions. A battery b , which may be of about two volts, and the low resistance primary b' of a transformer are arranged in series with the aforesaid contact pieces.

b^2 is the secondary winding which is arranged in the transmitting line with the receiver b^3 .

In the arrangement shown in Fig. 2, the vibratory or moving contact piece a^2 is arranged on one extremity of a pivotally mounted lever a^7 , which is adapted to preserve the faces of the contact pieces in proper operative relation so as to permit of the requisite movement of the vibratory contact piece a^2 relatively to the fixed or stationary contact piece a^3 , which is carried by the eas-

ing a^8 of the transmitter. As in the previous arrangement a cell a^5 is formed between the contact faces, in which cell is placed a few grains of the aforesaid alloy or metal.

With a view to avoiding heating of the contact pieces, there may be associated with, say, the stationary contact piece, a chamber or conduit a^9 (Fig. 3) through which is circulated a suitable cooling medium, thereby maintaining the contact pieces at a suitable temperature.

In applying the invention to a relay, one arrangement is shown in Fig. 4 in which a vibratory member such as a steel reed c is disposed in the circuit of a battery c' and adapted to be indirectly acted upon by the voice through the line electromagnet c^2 arranged adjacent thereto. The reed c is secured to the framing c^3 of the relay and has a conducting contact piece c^4 having a facing of iridium, the said contact piece being disposed opposite to a similarly faced fixed or stationary contact piece c^5 carried by the member c^6 , which is secured to the frame or support of the relay. The space between the contact pieces is arranged as a cell or chamber d , being closed or enveloped by some material d' that is capable of yielding readily when the contact pieces are subjected to relative vibration by the electric or sound waves. India rubber may be employed in this connection but any other material or contrivance adapted to perform the desired function may be employed. The cell d may contain a few grains of osmium-iridium as in the previously described arrangements. Owing to the resiliency of the reed, the distance between the faces of the contact pieces is varied by the action of the aforesaid waves, and, as a result of the movements of the contact piece c^4 , the grains are alternately pressed together and released from pressure; the passage of the electric current is facilitated by the small resistance of the alloy, and variations in the strength of the current are facilitated owing to the hard and elastic character of the alloy enabling the same to instantly recover its original form or state when the pressure to which it is subjected is released.

The reed c is arranged in the circuit of a battery c' , of suitable voltage, and the contact pieces c^4 , c^5 of the relay are arranged in series with this battery and a receiver c^8 . The line electromagnet c^2 arranged adjacent to the reed c is energized in accordance with the electric or sound waves being transmitted in the line, and causes the reed to vibrate in accordance with such electric or sound waves.

In the arrangement shown in Fig. 5 the initial pressure between the contact pieces, and hence the normal resistance in the circuit of the battery c' , is controlled electrically in a manner similar to that provided for adjusting the conducting space referred to

to in the specification of my British Patent No. 11135 of 1908. This arrangement consists of a special winding d^4 provided on the electromagnet c^2 and arranged in the battery circuit so that the current in said circuit will energize the electromagnet and adjust the pressure on the contact pieces. The opposing faces of the contact pieces may be either horizontal or vertical, but the above mentioned electrical method of adjusting the pressure is especially applicable to constructions in which the said opposing surfaces are vertical.

The initial pressure on the contact device may in some cases be obtained by relying on the weight of the grains themselves if suitably arranged and of sufficient size and quantity; or the initial pressure may be obtained directly by means of a screw adjustment.

A form of the relay when a single point of contact is employed is shown in Fig. 6, the contact pieces e , e' being respectively mounted on arms or carriers e^2 , e^3 arranged on the frame e^4 of the relay. The upper arm or carrier e^2 is pivoted on the aforesaid frame and carries a weight e^5 for adjusting the initial pressure between the contact pieces, this weight being counterbalanced by an adjustable weight e^6 . The contacts, which are of osmium-iridium, are arranged in series with the low voltage battery e^7 and the receiver e^8 . A winding f is provided on the magnet N and the line currents passing through the said winding are adapted to influence the magnet in accordance with the sounds being transmitted.

Fig. 7 shows a form of relay similar to that shown in Fig. 6 but in which the initial pressure between the contact pieces is not obtained by the action of gravity but by a spring; in this case the arm e^2 carrying the contact piece e is in the form of a blade spring and the initial pressure of the contact pieces is adjusted by means of the set screw e^6 which bears upon the aforesaid spring arm e^2 . The arrangement in other respects corresponds with that already described. The electrical control of the initial pressure set forth in connection with Fig. 5 is equally applicable to relays of the single contact type.

In using grains of osmium-iridium alloy it is found that owing to the hardness, elasticity and good conductivity, the vibratory contact piece is much sharper and much more definite in its action or movement; the metal contact pieces closing up and opening out much more readily than carbon contacts do, thus allowing the construction of a telephone relay that can be operated efficiently by less energy than heretofore. The hardness and elasticity of the material composing the points or surfaces of contact enables the said material to expeditiously

or instantaneously resume its shape, and the contact device to quickly resume its original resistance of contact after the deformation resulting from the pressure incidental to the vibrations hereinbefore referred to. It is therefore advantageous to have the faces and the grains of great hardness, the grains as well as the faces being of such a character as to enable them to receive the pressure and to readily recover therefrom. As hereinbefore stated the best results are obtained when the resistance of the contact device bears the same relationship to the resistance of the circuit in which it is included as exists between the resistance of a circuit in which an ordinary carbon contact device is employed and the resistance of the carbon contact device. Since in accordance with the present invention the contact device is metallic and consequently of low resistance in comparison with a carbon contact device, the resistance of the circuit in connection with it should be correspondingly reduced.

It is because it is possible to use a contact device of such comparatively low resistance and to correspondingly reduce the resistance of the circuit connected with it that the received sounds are so much magnified and their definition so greatly improved.

As the invention embodies a device of low resistance the value of which can be varied by variations of pressure between two parts of the device, the latter can be used in systems other than telephonic in which such an effect is desired, and can for instance be used under certain conditions in telegraphy.

What I claim and desire to secure by Letters Patent of the United States is:—

1. In electrical apparatus for magnifying electric waves or vibrations or producing the same by conversion from corresponding sound waves, a variable resistance contact device comprising fragmentary osmium and iridium alloy.

2. In electrical apparatus for magnifying electric waves or vibrations or producing the same by conversion from corresponding sound waves, a variable resistance contact device comprising two hard surfaces and a granule of osmium-iridium alloy interposed between the said surfaces.

3. In electrical apparatus for magnifying electric waves or vibrations or producing the same by conversion from corresponding sound waves, a variable resistance contact device comprising two hard surfaces, and granules of osmium-iridium alloy interposed between the said surfaces.

4. In electrical apparatus for magnifying electric waves or vibrations or producing the same by conversion from corresponding sound waves, a variable resistance contact device comprising two surfaces of iridium and a granule of osmium-iridium alloy interposed between the said surfaces.

- 4
- 5. In electrical apparatus for magnifying electric waves or vibrations or producing the same by conversion from corresponding sound waves, a variable resistance contact device comprising two surfaces of iridium and granules of osmium-iridium alloy interposed between the said surfaces.

In testimony whereof I affix my signature in presence of two witnesses.

SIDNEY GEORGE BROWN.
